UNITED STATES PATENT OFFICE.

FRANK C. WAGNER, OF ANN ARBOR, MICHIGAN.

ELECTRIC REGULATOR.

SPECIFICATION forming part of Letters Patent No. 399,224, dated March 5, 1889.

Application filed October 29, 1888. Serial No. 288,659. (No model.)

To all whom it may concern:

Be it known that I, FRANK C. WAGNER, a citizen of the United States, residing at Ann Arbor, county of Washtenaw, and State of Michigan, have made a new and useful invention in Regulators for use on Electrical Circuits, of which the following is a specification.

My invention relates particularly to regulators of that type of devices which are actuated by or through the thermal effects of a current of electricity.

The nature and object of my invention will be fully understood by referring to the following specification and accompanying drawings, but particularly pointed out in the claims at the end of said specification.

In the drawings, in which like letters of reference wherever used indicate like parts, Figure 1 is a side elevation of my improved regulator, and Fig. 2 a plan thereof. Fig. 3 is an end elevational view of the same; and Fig. 4 is a side elevational view of a modified form, showing a shunt-wound dynamo and a working-circuit, the whole being operatively connected for the regulation of the dynamo, while Fig. 5 is an end elevational view of the regulator shown in Fig. 4.

E is the base-board which sustains the operative parts of my improved regulator.

A and A' are metallic standards rigidly secured to the opposite ends of said base-board, and B is a metallic wire of high resistance and of such nature as to be readily influenced by the thermal effects due to the flow of an electrical current. This wire B is connected at its opposite ends under strain to the upper ends of the metallic standards A, A', and carries at its middle, as shown in Figs. 1 and 2, a weight, P, rigidly secured to it.

C' C² C³, &c., are metal blocks soldered or otherwise rigidly secured to the wire B at substantially equal distances apart on either side of the weight P. These metal blocks constitute a series of electrical contact-points adapted to contact against a corresponding series of points, D' D² D³, &c., lying directly below them, said points being in the nature of metallic springs secured by screws to the base-board E, and connected, respectively, by resistance-coils R' R², &c., to R¹⁰, with a wire,

K, also secured to said base-board F' F², &c. To F¹⁰ are screws extending through the free ends of the contact-springs D' to D¹⁰, inclusive, and into the base-board E, forming in 55 this instance back-stops for said spring-contacts.

G is the incoming wire from the working-circuit to the regulator, and H is the outgoing wire from the regulator to said working-circuit, in which is located in this instance a translating device, M', for which the flow of the current is to be regulated through the wire K and the shunt-resistances R' to R¹⁰, 60 inclusive, as will be explained. 65

Suppose M' to be one of a series of electrical translating devices, as motors or electric lights, situated in a working-circuit, G H, and that some one or more of the outlying translating devices have been thrown out of 70 circuit or short-circuited. In this event there might be a dangerous increase of current through the translating devices M' were it not for the regulator, the operation of which I will now describe. An increase of current 75 in the working-circuit G H, in the manner indicated, would cause the thermal conductor B to be heated and through the agency of the weight P bring one or more of the metallic pieces, C' to C¹⁰, into electrical contact with the 80 metal springs D' to D¹⁰, thus shunting more or less of the current through the rheostats R' to R¹⁰ around the translating devices M'. 85

The modified form shown in Figs. 4 and 5 is designed for use where it is found necessary to increase the resistance in the shunt when an increase in the electro-motive force occurs in the working-circuit. M represents a shunt-wound dynamo having its armature in the working-circuit and its field-magnets 90 in the regulator-circuit. I is a metallic bar electrically connected to a conductor, L, which also constitutes a part of the field-magnet circuit. In this instance the metallic contact-springs D' to D¹⁰, inclusive, lie entirely above 95 the screws F' to F¹⁰, inclusive, the heads of which are located at different elevations. The rear ends of these metallic springs are connected to the rheostats R' to R¹⁰, inclusive, and in turn to shunt-wire K, as before, said 100 wire K being connected to the armature-circuit, as shown, while the thermal wire B is

connected directly in the working-circuit. The weight P is attached to the thermal wire B, as before, but carries in this instance two standards, U, which are attached at their upper ends to the rod L, but insulated therefrom by insulation, V. The operation of this modified form will be understood on examining Fig. 4. It is quite clear, as shown in this figure, that any increase in the electro-motive force in the working-circuit due to any external change causes an increased flow of current through the thermal wire B, thereby permitting the weight P to lower the rod I until one or more of the contact-springs D' to D¹⁰ is 15 or are brought into mechanical contact with the heads of screws F' to F¹⁰, and in that manner breaking the circuit successively between said contact-springs and the bar I until the resistance in the field-circuit has been increased a sufficient amount to counterbalance 20 the effects due to the increased electro-motive force in the working-circuit.

It is obvious that this regulator is adapted for use in many ways which will at once suggest themselves to persons skilled in the art— 25 as, for instance, it might be used with an electric meter where the meter is located as shown at M' in Fig. 2, in which event the reading of the meter would be directly proportional to the current strength instead of the square 30 thereof. The form shown in Fig. 4 may be used as an alternating-current constant-potential regulator in the following manner: Suppose the entire primary is the actuating-current. Then as the primary current increases the resistance of the exciting-current 35 is diminished, and an increased total electro-motive force results, sufficient to compensate

for the loss of potential due to wiring. I do not limit myself, therefore, to any special 40 mechanism for adapting the principle herein described, and simply show the forms of apparatus disclosed to best exemplify the application of this principle to regulators generally as applied on electrical circuits. 45

What I do claim, and desire to secure by Letters Patent of the United States, is—

1. An electrical regulator consisting of a thermal conductor located in circuit with a translating device requiring current regulation, in combination with a multiple-arc shunt around the translating device, and two sets of contacts, one of which sets is borne by the thermal conductor and the other connected to the multiple-arc branches of the shunt and adapted to contact successively, substantially as described. 55

2. A thermal electric regulator consisting of the following elements: a thermal conductor carrying multiple contacts and a shunt having multiple contacts located near the first 60 set of contacts, substantially as described.

3. In a regulator, the combination of a thermal conductor located in the main circuit with the device requiring current regulation, 65 a shunt around said device, and circuit-varying connections between the shunt and the thermal conductor, whereby the current is shunted around the device requiring regulation in proportion to its flow, substantially 70 as described.

FRANK C. WAGNER.
